JAR TOP

Anthony Hudoba, Struthers, Ohio

Application October 14, 1937, Serial No. 168,926

1 Claim. (Cl. 215—91)

This invention relates to jar tops.

The principal object of this invention is the provision of a jar top that may be easily placed upon and removed from a jar.

5 A further object of this invention is the provision of a jar top that may be clamped upon a jar.

A further object of this invention is the provision of a jar top that may be secured by means 10 of a clamp and a slidable wedge member cooperating therewith.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, 20 without departing from the spirit of the invention.

The invention is illustrated in the accompanying drawing, wherein:—

Figure 1 is a top plan view of the jar top in 25 position upon the top of a jar.

Figure 2 is a side elevation, with parts broken away, of the jar top in position upon a jar.

Figure 3 is a cross section taken on line 3—3 of Figure 1.

30 By referring to the drawing it will be seen that there is provided a clamp 1 having down-turned portions 2 and 3, the extreme ends 4 of which are turned inwardly in order to fit underneath a peripheral flange 5 of a jar 6. It will be seen that the down-turned portion 3 is relatively 35 shorter than the down-turned portion 2. By referring to Figure 1 it will be seen that there is positioned upon the clamp 1 a slidable wedge member comprising a flat pressure member 7 and a slightly curved pressure member 8. These pressure members 7 and 8 are formed of one piece 40 of material and spaced apart by a slide member 9 formed by cut-out portions, between the ends of the pressure members 7 and 8, turned upwardly and inwardly so as to fit loosely upon the clamp 1.

By referring to Figure 3 it will be seen that the slightly curved pressure member 8 makes pressure contact at its extreme ends 10 with a jar top 11. By referring again to Figure 1, it will be seen 50 that the jar top 11 is provided with raised portions 12 and 13, the portion 13 being slightly smaller than the portion 12. The raised portions 12 and 13 are spaced apart and have their inner edges 14 and 15 parallel to each other in order

to form a slide-way for the flat pressure member 7 and to hold the clamp centrally upon the jar top 11.

In placing the device upon the jar 6, the slide member 9 is slid outwardly so that the slightly curved pressure member 8 comes in contact with the down-turned portion 2. The clamp 1 is then slid onto the jar top 11, the outer edge 16 of the flat pressure member 7 sliding along an edge 17 of the raised portion 13. The raised portion 12 [10] being slightly larger than the raised portion 13, an extreme end 18 of the flat pressure member 7 will be stopped by coming in contact with the inner edge 14 of the raised portion 12. The clamping means is then completed by sliding the [15] pressure members and connecting slide member into the slide-way between the raised portions 12 and 13. A tightening of the top 13 takes place compressing the top firmly and evenly against a rubber ring 19 positioned between the upper edge 20 of the jar 6 and the lower surface of the jar top 11.

By referring to Figure 1 it will be seen that the jar top is shown in a clamped position. The flat pressure member 7 presses downwardly upon 25 the jar top 11 while the extreme outer ends 10 of the curved pressure member 8 form compression points so that the jar is firmly held under a three point compression. It is obvious that in removing the clamp from the jar top it is necessary only to slide the pressure members 7 and 8 and connecting slide 9 back against the down-turned end 2, thereby releasing the pressure and allowing the clamp to be slid off. 30 35

What I claim is:—

In a jar top, a clamp for said top, relatively short downwardly extending and inturned ends on said clamp adapted to fit underneath a peripheral flange of a jar, one down-turned portion 40 being relatively longer than the other, a curved pressure member and a flat pressure member together with a slide member formed by cut-out portions between the ends of the pressure members turned upwardly and inwardly to fit 45 loosely upon the clamp, a pair of raised portions on said top, one larger than the other, said smaller raised portion adapted to allow the flat portion to slide past it and the larger portion adapted to form a stop for the flat portion when 50 it reaches the center of the jar top where it can be slid between the raised portions, substantially as described.

ANTHONY HODOBA.
